US0D1051826S

(12) **United States Design Patent** (10) **Patent No.:** **US D1,051,826 S**
(45) **Date of Patent:** **** Nov. 19, 2024**

(54) **CHARGING ADAPTER**

(71) Applicant: **Shenzhen Kule Youpin Technology Co., Ltd**, Shenzhen (CN)

(72) Inventor: **Zhichao Wang**, Shenzhen (CN)

(**) Term: **15 Years**

(21) Appl. No.: **29/863,506**

(22) Filed: **Dec. 20, 2022**

(51) **LOC (14) Cl.** **13-02**

(52) **U.S. Cl.**

USPC **D13/107**

(58) **Field of Classification Search**

CLAIM

The ornamental design for a charging adapter as shown and described.

DESCRIPTION

FIG. 1 is a perspective view of a charging adapter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the charging adapter that form no part of the claimed design.

1 Claim, 8 Drawing Sheets
